UNITED STATES PATENT OFFICE.

LOUIS W. DOWNES AND ALFRED W. FAXON, OF PROVIDENCE, RHODE ISLAND; SAID FAXON ASSIGNOR TO D & W FUSE CO., OF PROVIDENCE, RHODE ISLAND, A CORPORATION OF RHODE ISLAND.

OIL-SWITCH AND FUSE.

1,192,397.

Specification of Letters Patent. Patented July 25, 1916.

Application filed June 25, 1914. Serial No. 847,286.

To all whom it may concern:

Be it known that we, LOUIS W. DOWNES and ALFRED W. FAXON, citizens of the United States of America, and residents of 5 Providence, Rhode Island, have invented a new and useful Improvement in Oil-Switches and Fuses, which invention is fully set forth in the following specification.

This invention relates to electric switches 10 and fuses.

Among the objects attained thereby are the following:—The provision of a structure in which the fuse-link is adapted upon disruption by excessive current to break the 15 circuit in an arc-suppressing liquid, such as oil, the structure being at the same time operable as a switch to open the circuit at terminals submerged in the arc-suppressing liquid. The structure is thus operable from 20 the exterior of an inclosing casing without opening said casing. The fuse-link is connected between contacts or terminals which are moved into and out of engagement with relatively fixed circuit terminals when the 25 structure is operated as a switch or for the insertion of a new fuse-link. The cover of the inclosing casing must be fully and tightly closed before the terminals between which the fuse-link is connected can be engaged with the circuit terminals. The cover 30 is automatically locked tightly closed by movement of the fuse-link or switch terminals into engagement with the circuit terminals and remains so locked until after 35 such terminals are disengaged, whereby the fuse cannot possibly be disrupted with the cover open, or with it closed and unlocked, hence avoiding any discharge of oil from the structure upon blowing of the fuse. These 40 and other objects are realized in the structure of the present invention.

What is now regarded as the preferred mechanical expression or embodiment of the invention is illustrated in the accompanying 45 drawings, wherein—

Figure 1 is a vertical central sectional view; Fig. 2 is a similar view approximately at right angles to the plane of section of Fig. 1; Fig. 3 is a fragmentary view, in elevation 50 and section, of the upper portion of the structure showing the fuse-link carrier and

associated movable elements swung upward to a position to open the switch, with the cover of the casing closed; Fig. 4 is a similar view with the cover partly open and illustrating the action of means which prevent the closing of the cover with the parts out of correct position for closing with safety; this figure also illustrates gas venting means on the cover not shown in other figures; Fig. 55 5 is a detail perspective view of the insulating frame on which the circuit terminals are mounted; and Fig. 6 is a detail sectional view on line 6—6 of Fig. 1.

10 is a cup-like casing, preferably of cast 65 metal, having at one side notched lugs or ears 11, 11 for fastening the structure to a building, pole, or other support. Terminal conductors 12, 13 enter said casing by passing upward through bushings 14 (only 70 1 of which shows in the drawings), the joint between the conductors, bushings and casing being sealed liquid-tight in any suitable way.

15 is an insulating base, frame or support 75 of approximate E-shape of any suitable insulating material, preferably such as that commercially known as "molded insulation", composed of a fibrous base of ingredients of powdered substances, such as ground asbestos, and a binding compound, such as rubber or bakelite. The support 15 has thereon three exterior lugs 16, 16, 16 which rest against (with interposed packing) a ledge 17 extending around three sides of the interior of the casing 10. A screw 18 passes through each lug 16 into the ledge 17, as illustrated in Fig. 2, thus securing the support 15 rigidly in place. The end wings 19 and 20 of the support 15 are formed with 80 90 inwardly projecting lugs 21 and 22, respectively, each lug having therethrough two vertical perforations. 23 is a terminal brush riveted to the depending arm 24 of a horizontally disposed plate 25 which bears 95 against the upper surface of the lug 21 (Fig. 1). A metal strip 26 fits against the plate 25 and another metal strip 27 fits against the under edge of the lug 21. A screw 28 (Fig. 6) passes downward through the 100 plates 25, 26, one of the perforations in the lug 21, and into screw-threaded engagement

with an opening of plate 27. Another screw 29 passes upward through plate 27, the other perforation in lug 21, through plate 25 and into screw-threaded engagement with plate 26, and then into an elongated nut 30. The inner end of conductor 12 is electrically joined in any suitable way to the upper end of nut 30. Duplicates of these parts—terminal brush 23, plates 25, 26, 27, screws 28, 29, and nut 30—are associated with the lug 22 and the inner end of conductor 13, the terminal brush in this instance being designated by the numeral 31.

The casing 10 has a cover 50 hinged thereto at 51 and adapted to be clamped in its closed position by the usual form of swinging bolt 52 having a wing nut for engagement over projecting lugs on the cover.

53 and 54 are horizontal parallel shafts 20 extending across the interior of the cover and journaled in bearings in the opposite side walls thereof. An operating lever or handle 55 is fastened to one end of the shaft 54 outside of the casing. A fuse-carrier and 25 movable switch member 60 is clamped about and thus rigidly secured to the shaft 54 by a bolt 61, and is forked or slotted at 62 whereby in its normal vertically depending "on" position it straddles the middle wing 30 63 of the E-shaped frame 15, said wing 63 depending considerably below the end wings 19 and 20 and constituting an insulating partition or barrier between the circuit terminals 23 and 31 disposed on opposite sides 35 thereof. The fuse-carrier 60 is made of any suitable insulating material, but preferably hard wood, such as birch, impregnated (in vacuum) with a suitable oil, such for example as the well-known "transformer oil." 40 64 is an integrally formed enlargement at one side of the carrier 60 providing an overhanging ledge against the under side of which a fuse terminal piece 65 is secured by a screw 66, the outer surface of said terminal 45 65 being adapted to make electrical engagement with the terminal brush 23 when the parts of the structure are in the position shown in Figs. 1 and 2. An arm 67 depending from the terminal piece 65 has a screw 50 68 with a clamping nut 69 positioned on the inner end thereof between the depending arm 67 and the opposing face of the carrier 60. At the other side of the carrier 60 there is a similar enlargement 64 and associated 55 therewith a similar fuse terminal piece 65, screw 66, arm 67, screw 68 and nut 69. A fuse-link bent around the lower end of the fuse carrier 60 and across the lower end of the barrier 63, when the parts are in the position shown in Figs. 1 and 2, is composed of two end sections 70 and 71, notched or hooked as shown in dotted lines (Fig. 4) for engagement with the screws 68, 68, and a connecting middle section 72 which may 60 overlap and be soldered to the end sections, 65

as illustrated in Fig. 1. The end sections 70 and 71 may be of copper and the middle section 72 of readily fusible metal.

75 is an inwardly projecting flange along the edge of one side of the upper open end of the casing 10; there is a similar flange 75 at the opposite side of the casing. Each of these flanges is cut away or notched at 76 and 77 (Fig. 4). The shaft 53 carries at its opposite ends, inside of the cover, two arms 78 and 79, each having at its lower end an outwardly projecting cylindrical knob or extension. The shaft 54 similarly carries at its opposite ends, inside the cover, two arms 80 and 81, each having at its lower end an outwardly projecting cylindrical knob or extension. A link 82 joins the arms 79 and 80, whereby the shafts 53 and 54 and their arms move in unison when the operating lever or handle 55 is actuated.

85 In the normal closed or "on" position of the switch, shown in Figs. 1 and 2, with the circuit brush terminals 23 and 31 in engagement with the fuse link terminals 65, 65, the operating handle 55 and the arms 80, 81 on 90 the shafts 53 and 54 stand in an approximately vertical position, with the knobs or extensions of the arms 78 and 79 engaging under the inwardly projecting flanges 75, 75 at opposite sides of the casing and thus 95 securely locking the cover in its closed position.

100 It is intended that the casing shall be filled with an arc-suppressing liquid, such as oil, approximately to the "oil-level" indicated on the drawings, thus submerging not only the fuse-link but also the circuit and fuse-link terminals, when the parts are in the position shown in Figs. 1 and 2. To open the switch—both when the structure is 105 being operated merely as a switch and preparatory to opening the cover for the insertion of a new fuse-link in place of one which has been disrupted—the operating handle 55 is actuated to rotate the shafts and swing 110 the parts associated therewith to the approximately horizontal "off" position shown in Fig. 3. In such movement the circuit and fuse terminals are disengaged below the level of the liquid, which latter is thus enabled to suppress any arc which may tend 115 to form upon the separation of the terminals. After the terminals have thus been disengaged and near the end of the movement which brings the parts to the position 120 shown in Fig. 3, the knobs at the lower ends of the arms 78 and 79 pass out from under the edge of the overhanging flanges 75, 75 and upward through the notches 76, thereby 125 unlocking the cover which may thereupon be opened if desired. Assuming the cover to have been opened for the insertion of a new fuse-link or for other purpose, the cover can only again be closed with the parts 130 brought to the position shown in Fig. 3; and

in such position when the operating lever is actuated to swing the fuse carrier downward to engage its terminals with the circuit terminals, the knobs on the arms 78 and 79 are automatically swung downward through the notches 76 and under the overhanging flanges 75, 75, thus automatically locking the cover in its closed position before the terminals become reengaged. Therefore, the cover can only be closed with the parts in the proper position to afford the desired protection. As illustrated in Fig. 4, for example, the parts are in an incorrect position and hence the knobs at the lower ends of the arms 80 and 81 contact the flanges 75, 75 and prevent the closing of the cover; whereas were the parts in the correct position, as illustrated in Fig. 3, said knobs would pass downwardly through the notches 77 of the flanges.

As is well known, the disruption of a fuse-link by an excessive current is accompanied by the instantaneous formation of pressure-generating gases. In Fig. 4 (though not in other figures of the drawings because of lack of space), the casing is provided with a suitable vent for the ready escape of such gases to thereby prevent internal pressure which might become dangerous and destructive. A cup-like member 90 has a tubular stem 91 tapped and screw-threaded through the cover 50. A cap 92 covers the upper end of the cup-like part and has a flange 93 depending about the upwardly projecting flange 94 which latter constitute the side walls of the cup-like member. There is sufficient clearance between the flanges to constitute a vent passage or space for the escape of gas. A shorter flange 95 depends from the cap 92 inside of the upper edge of the flange 94. The parts thus described inclose a vented chamber 96 with which the main chamber of the structure communicates through the tubular stem 91 and a tube 97, preferably brass. Tube 97 terminates at its upper end under a dome-like downwardly deflecting surface 98 of the cap 92 and has a filling 99 of reticulated material, preferably fine wire gauze, either in the form of disks, cups, or spirals. Upon disruption or blowing of the fuse-link in the main chamber, gas and oil in a finely divided commingled state are forced upward into the tube 97, where the gauze acts to arrest the particles of oil, though permitting the gas to pass on upward and out of the chamber 96 to the atmosphere. Such small particles of oil as may, in extreme cases, be carried upward and out of the tube 97 into the chamber 96 will contact with the dome-like surface 98 and be deflected to the bottom of said chamber and thence drain back into the main chamber through perforations 100, 100 in the side wall of the brass tube 97 just above the bottom of chamber 96.

The gas-vent means thus described, and illustrated in Fig. 4 of the drawings, are not claimed in this application but are claimed in our application filed May 27, 1914, Serial No. 841,335.

What is claimed is:—

1. The combination of a casing, circuit terminal contacts therein, a cover for said casing, an oscillating insulating member on said cover adapted in normal position to depend below said terminal contacts, contacts on said oscillating member adapted to engage said terminal contacts, and a fuse member connecting the contacts on said oscillating member and extending around the portion thereof adapted to depend below the terminal contacts.

2. In an oil switch, a casing containing oil, circuit terminal contacts located in said casing below the surface of the oil, a cover for said casing, an oscillating member on said cover adapted to depend below said terminal contacts when in normal position, contacts on the sides of said oscillating member adapted to engage said terminal contacts, and a fuse member connecting said contacts and adapted to be located below the terminal contacts when the switch is in "on" position.

3. In an oil switch, a casing containing oil, an insulating block in said casing, terminal contacts associated with said block, a cover for said casing, rotating shafts in said cover, a two-legged insulator having side projections thereon and mounted on one of said shafts and adapted to move therewith, electrical contacts attached to said projections and adapted to engage said terminal contacts, and a fuse member connecting said electrical contacts and adapted to pass below the ends of said insulator, said insulator straddling a portion of the non-conducting member when in vertical position.

4. In an oil switch containing a fuse, the combination of a casing with oil therein, an insulating block in said casing, terminal contacts mounted on said block, a cover for said casing, a shaft in said cover adapted to be moved by a member extending outside said cover, an insulating member carrying electrical contacts associated with said shaft, said contacts engaging said terminal contacts, and a fuse joining said electrical contacts and movable with said insulating member into the lower part of said casing.

5. In an oil switch containing a fuse, the combination of a casing with oil therein, an insulating block in said casing, terminal contacts mounted on said block, a cover for said casing carrying shafts adapted to be moved by an external member, an insulating member carrying electrical contacts associated with one of said shafts, said contacts adapted to engage the terminal contacts, a fuse joining said electrical contacts and mov-

able with said insulating member into the lower part of said casing, and lugs mounted on the other of said shafts adapted to interlock with inward projections on said casing 5 when the contacts are closed on each other.

6. In an oil switch containing a fuse, the combination of a casing having oil therein, an insulating block in said casing, terminal contacts mounted on said block, a cover for 10 said casing carrying shafts adapted to be moved by an external member, an insulating member carrying electrical contacts movable by said external member, said contacts adapted to engage the terminal contacts, a fuse joining said electrical contacts and movable with the insulating member into the lower part of said casing, and lug members on said shafts adapted to align with inward projections on the casing for 15 preventing opening of said cover when the switch is closed and for preventing closure when said cover is raised and said insulating member not in normal open position.

7. The combination of a two-part casing, 20 one of said parts being a cover; circuit terminals in the casing; a switch member in the casing and movable from an "on" to an "off" position with relation to said terminals; a fuse connecting parts of said switch 25 member and adapted to depend below said terminals when in "on" position; means extending to the exterior of the casing to actuate said switch member; and a pivotal locking device attached to one casing part 30 and actuated upon movement of the switch member to lock the cover closed in the "on" position of said member and to unlock the cover in the "off" position of said member.

8. The combination of a two-part casing 35 including a main casing part and a cover; circuit terminals in the casing; a switch member within the casing pivotally attached to and movable with the cover when the latter is opened and adapted to be swung on its pivot from an "on" position in engagement with the terminals to an "off" position out of engagement with said terminals; a fuse joining parts of said switch member and adapted to depend below said terminals when 40 in "on" position; means extending from said switch-member to the exterior of the casing for actuating the same; and a locking device pivoted to the cover and actuated upon movement of the switch member to lock the cover in the "on" position of said member and to unlock the cover in the "off" position of said member.

9. The combination of a two-part casing 45 including a main casing part and a cover; circuit terminals in the casing; a switch member within the casing pivotally attached to and movable with the cover when the latter is opened and adapted to be swung on its pivot from an "on" position in engagement with the terminals to an "off" posi-

tion out of engagement with said terminals; a fuse joining parts of said switch member and adapted to depend below said terminals when in "on" position; means extending from said switch member to the exterior of 70 the casing for actuating the same; and means pivoted to the cover and movable with the switch member to a position to prevent closing of the cover with said switch member in its "on" position. 75

10. The combination of a two-part casing including a main casing part and a cover; circuit terminals in the casing; a switch member within the casing pivotally attached to and movable with the cover when the latter is opened and adapted to be swung on its pivot from an "on" position in engagement with the terminals to an "off" position out of engagement with said terminals; a fuse joining parts of said switch member 80 and adapted to depend below said terminals when in "on" position; means extending from said switch member to the exterior of the casing for actuating the same; a locking device pivoted to the cover and actuated upon movement of the switch member to lock the cover in the "on" position of said member and to unlock the cover in the "off" position of said member; and means pivoted to the cover and actuated upon movement of the switch member to assume a position to prevent closing of the cover with 85 said switch member in its "on" position.

11. The combination of a two-part casing including a main casing part and a cover; 90 circuit terminals in the casing; two shafts journaled in the cover; a switch member within the casing on one of said shafts; means on the exterior of the casing to rotate said shaft and swing the switch member to "on" and "off" positions with relation to the terminals; connections from said shaft to the other shaft for rotating the latter; locking means on one shaft actuated by rotation thereof to lock the cover closed in the 95 "on" position of the switch member and to unlock the cover in the "off" position of said member; and means carried by the other shaft preventing closing of the cover with the switch member in its "on" position. 100

12. The combination of a casing; a cover therefor, an insulating frame or support open at one side; circuit terminals mounted upon said frame; a movable switch member mounted on said cover for engaging said 105 terminals and adapted to move into and out of the open side of said frame in shifting to its "on" and "off" positions and a fuse positioned below said terminals.

13. The combination of fixed circuit terminals; an insulating barrier or partition between said terminals; a slotted switch member movable from an "off" position to an "on" position astride of said insulating barrier and in engagement with said termi- 110 120 130

nals, and a fuse on said switch member adapted to depend below said member and said barrier.

14. The combination of an E-shaped insulating frame the middle wing thereof constituting an insulating barrier or partition; circuit terminals on the end branches of said frame respectively; a slotted switch member movable from an "off" position to an 10 "on" position astride of said insulating barrier and in engagement with said terminals,

and a fuse connecting parts of said switch member.

In testimony whereof we have signed this specification in the presence of two subscribers 15 and witnesses.
